US00D359144S

United States Patent [19]

Healzer et al.

[11] Patent Number: **Des. 359,144**

[45] Date of Patent: ** Jun. 6, 1995

[54] **COMBINED HAIR CLASP AND GARLAND RETAINER**

200829 2/1924 United Kingdom 132/275

[75] Inventors: **Janelle L. Healzer**, 200 Estes, Nixa, Mo. 65714; **Gaylen D. Healzer**, Nixa, Mo.**OTHER PUBLICATIONS**

"Hong Kong Enterprises", Oct. 1991; p. 470: 4th row from bottom; 5th from left: item 3118/F31.

[73] Assignee: **Janelle L. Healzer**, Nixa, Mo.*Primary Examiner*—Terry A. Wallace[**] Term: **14 Years***Assistant Examiner*—C. Tuttle[21] Appl. No.: **7,278***Attorney, Agent, or Firm*—Hovey, Williams, Timmons & Collins[22] Filed: **Apr. 21, 1993****CLAIM**[52] U.S. Cl. **D28/42**

The ornamental design for a combined hair clasp and garland retainer, as shown and described.

[58] Field of Search ..... **D28/39-43, D28/93; 132/273, 275-279****DESCRIPTION**[56] **References Cited**

FIG. 1 is a perspective view of the combined hair clasp and garland retainer hereof;
